UNITED STATES PATENT OFFICE

2,157,412

KNIFE HOLDER

Horner H. Hopkins, Des Moines, Iowa

Application November 12, 1937, Serial No. 174,172

1 Claim. (Cl. 211—87)

The principal object of my invention is to provide a handy knife holder that protects the sharpened edge of a knife blade and prevents possible injury to a person by completely covering and encasing the blade.

A further object of this invention is to provide a knife holder that is a simple and inexpensive support for a plurality of frequently used knives.

A still further object of my invention is to provide a knife holder wherein a plurality of knives may be readily disposed therein, or as equally easily removed therefrom.

A still further object of this invention is to provide a knife holder that is durable in use, economical in manufacture, and efficient in operation.

These and other objects will be apparent to those skilled in the art.

My invention consists in the construction, arrangement and combination of the various parts of the device, whereby the objects contemplated are attained as hereinafter more fully set forth, pointed out in my claim and illustrated in the accompanying drawing, in which:

Fig. 1 is a front view of my knife holder in use showing a plurality of knives therein by the dotted lines.

Fig. 2 is a side view of my knife holder in use and secured to a supporting wall or like.

Fig. 3 is a top plan view of the knife holder showing its plurality of grooves for receiving knives.

Fig. 4 is a bottom view of the knife holder.

Fig. 5 is a cross sectional view of my knife holder and more fully illustrates its construction.

In previous knife holders, there have been a number of drawbacks. These holders, in a number of cases, exposed the blades, thereby giving rise to a chance injury to both the knives themselves and to the users. In others, the knife blades come in contact with each other, causing them to become dull and nicked. Also, where a plurality of knives are reposed in a single rack, it is most difficult to get the right knife without pulling out a number of them to determine which is the right one. I have overcome such objections as will be appreciated and as hereinafter more fully set forth.

Referring to the drawing, I have used the numeral 10 to designate the back board or base portion of my device and having a hole 11 cut near its top center portion for receiving a screw or the like. In the drawing I show the knife holder held in position by means of a screw 12 threaded into a supporting member 13, but obviously, any

suitable means may be employed. The numeral 14 designates the block member secured to the back board portion.

This block member is one piece as shown in Fig. 5 of the drawing and has a plurality of parallel longitudinal channel grooves 15, 16, 17, 18 and 19, for receiving knives of different sizes. These grooves 15, 16, 17, 18 and 19 are cut in the block member 14 and lie adjacent and communicate with the back board 10. The central groove 10 is designed to receive a large knife, such as a butcher knife. The depth of this groove 15 is increased by an auxiliary communicating channel groove 20 cut in the back board 10 adjacent the groove 15 in block member 14. This auxiliary groove 20 extends from the lower end portion of the back board 10 to a point adjacent the upper end portion of the block member 14. By this construction, a receiving slot opening is provided capable of receiving and successfully holding a wide bladed knife without increasing the thickness of the block member. In manufacture, this is highly desirable as the block member may be made from 2" x 4" wood stock, thereby making for not only a compact device of minimum dimensions, but also making for economy in manufacture. Obviously, if the grooves 20 were not provided in the block member to provide for wide bladed knives, the devices would have to be made from wood not of standard thickness and this would add greatly to the cost and bulk of the device. The grooves 15, 16, 17, 18, and 19 are arranged in spaced relationship to each other and are formed in the block member before the block member is secured to the back board. These channel grooves which are arranged parallel with each other in spaced relationship, communicate with the outside top and outside bottom of the block member and extend the full length of the block member. The block member may be of any suitable design but I recommend that its upper outer end portion be rounded as shown in Fig. 2, as one standing in front of the device may easily observe the knife receiving slot openings thereby facilitating the placement of the knives in the holding slot openings.

By the block member being formed from a single piece of wood or like, the channel grooves 50 will not be communicating with each other and therefore, each knife blade will be successfully held free of engagement with another knife.

I have used the numeral 21 to designate knives with their blades engaging the slot openings and 55

their handles engaging and resting on the upper end of the block member as shown in Fig. 1.

The practical operation of my device is as follows: The holder may be secured to the wall or cupboard, or may lay flat on a horizontal support. The center groove 18 is capable of receiving a large knife such as a butcher knife. Such a knife is inserted point downwardly. In most large knives such as a butcher knife, the point 10 curves out a substantial distance from the back of the knife blade, so that the back of the blade is not all in the same plane. The knife would ordinarily bind if it weren't for this auxiliary groove 28 to receive the tip portion. In knives 15 of a smaller size, the auxiliary groove is not used in connections with the grooves in the block member. Obviously, however, auxiliary grooves may be used if needed. The smaller knives are inserted in the same manner as the large one.

20. In the drawing, I show the two outer knife receiving slots smaller than the two knife receiving slots adjacent to them respectively and with the center receiving slot larger than any of them. Obviously, the user knows that the knives in the 25 outer sides of the device are smaller knives than those next to them and that the central knife is the largest of all the knives.

This facilitates the easy selection of the knife

desired. When a knife is needed, it is merely manually pulled outwardly and away from its holding and supporting slot opening. When one is through using the knife, it is merely necessary to replace it in its respective slot opening in the device.

Some changes may be made in the construction and arrangement of my improved knife holder without departing from the real spirit and purpose of my invention, and it is my intention to cover by my claim any modified forms of structure or use of mechanical equivalents which may be reasonably included within their scope.

I claim:

In a device of the class described, an elongated block member; said block member being of various thicknesses in cross section, a plurality of slot grooves cut in the rear side of said block member and extending the longitudinal length through the block member; said slot grooves being of various depths in proportion to the relative thickness of said block member in cross section, and a back board secured over the rearward side of said block member extending beyond its marginal edges and having a groove cut therein coincidental with one of the grooves cut in said block member.

HORNER H. HOPKINS.
